SIGNAL CONTROLLED PRINTING APPARATUS

Henry L. Tholstrup, Rochester, N. Y., assignor to
 International Business Machines Corporation,
 New York, N. Y., a corporation of New York

Application December 22, 1944, Serial No. 569,288

7 Claims. (Cl. 197—74)

This invention relates generally to signal controlled printing apparatus.

One example of apparatus of the above type is disclosed in my copending application Serial No. 492,896 filed June 30, 1943, and includes a typewriter which is operated automatically by signal impulses produced as a result of the sensing of code designations previously recorded in a record tape according to a predetermined code system. This example also includes a cyclically operable tape reader which operates to sense successively the recorded code designations in the tape and thereby to control the operation of the typewriter. In practice any desired message, such as a letter, which it is desired to transcribe, is first recorded in the record tape as code designations representing, respectively, the different characters to be printed and the required functional operations of the typewriter. When a tape bearing such a message is fed through the reader, the message is transcribed on a copy sheet in the typewriter in the desired finished form.

The character key levers of the typewriter disclosed in said copending application control corresponding type bars and the latter carry both upper and lower case type. For the purpose of controlling the selective printing of upper and lower case characters a shift code designation in the tape operates the shift lever of the typewriter and the latter adjusts the typewriter so that all character code designations in the tape following the shift code, will provide for printing upper case characters. Also, the sensing of a shift-release code designation in the tape returns the typewriter to its normal or lower case condition so that the sensing of subsequent character code designations in the tape will result in the printing of the lower case characters.

An object of the present invention is to provide a signal controlled printing apparatus which includes a new and improved means for effecting automatically case shifting operations in response to special code designations.

A further object is to provide a case shifting means for signal controlled printing apparatus which is relatively simple in construction and which is highly effective and dependable in operation.

According to one specific aspect of the present invention, it may be considered as being an improvement over the means for controlling and effecting case shifting which is embodied in the disclosure of my said copending application. It is noted, however, that in so far as certain of the broader aspects are concerned, the present inven-

tion may be embodied in a wide variety of different kinds of signal controlled printing apparatus.

Other objects of the invention will be pointed out in the following description and claims and illustrated in the accompanying drawings, which disclose, by way of example, the principle of the invention and the best mode, which has been contemplated, of applying that principle.

In the drawings:

10 Fig. 1 is a plan view showing the invention as embodied in the reader-controlled typewriter disclosed in my copending application, mentioned previously;

15 Fig. 2 is a view showing a strip of tape in which is recorded all of the required character and functional code designations of a typical code system which may be used to control the apparatus of the preferred embodiment;

20 Fig. 3 is an enlarged fragmentary vertical sectional view through the typewriter and showing the mechanisms for effecting case shifting;

25 Fig. 4 is a fragmentary plan view showing the key levers and related parts which control the operation of the case shifting mechanism;

30 Fig. 4a is a fragmentary vertical section taken on the line 4a—4a of Fig. 4, and illustrating the shift-release key and associated mechanism; and

35 Fig. 5 is a wiring diagram showing the various electrical circuits for effecting case shifting and shift release operations in response to the sensing of special code designations in a record tape, the view also showing diagrammatically certain parts of the reader and illustrating how the sensing of the tape is effected.

40 Before considering in detail the construction and operation of the illustrated embodiment of the invention, it will be helpful to consider first one practical example of a combinational hole code system by means of which any desired message, such as a letter, may be recorded on a record strip or tape. In Fig. 2, a portion of a record tape 10 is shown and punched in the tape are all of the code hole designations which represent, respectively, the characters and the functional operations of the typewriter which is disclosed in plan in Fig. 1. As shown, the combinational hole code system is based on six code positions which are indicated at both ends of the tape 10 by the reference numerals 1 to 6 inclusive. Each code designation is arranged in a vertical column or recording field and opposite each field bearing the code designation and below the lower edge of the tape 10, has been placed the particular character or typewriter function corresponding to the code designation in that

field. The smaller holes 11 at the center of the tape 10 and within each of the several recording fields are punched in the tape for the purpose of facilitating the feeding of the tape lengthwise during the reading or sensing operation. In so far as the present invention is concerned the code designations may be punched in the tape by any suitable means such, for example, as by the typewriter controlled tape punch disclosed in my co-pending application Serial No. 492,895 filed June 30, 1943.

In Figs. 1, 3, 4, 4a, and 5 of the accompanying drawings, the invention is shown as embodied in a reader controlled typewriter like that shown in my aforementioned copending application Serial No. 492,896, of which this invention, according to a specific aspect thereof, may be considered as an improvement. In Fig. 1 the reference numeral 12 indicates a cyclically operable tape reader, the numeral 13 indicates a typewriter the operation of which is controlled automatically by tape reading operations of the reader 12, and the character RT indicates a cable connection between the reader and typewriter and containing the required circuit wire connections between electrical devices located in the two structures.

It is noted that, with the exception of the means provided herein for effecting and controlling the operation of the case shifting mechanism, the construction and operation of the present apparatus is the same as that disclosed in my said copending application Serial No. 492,896. Consequently, in view of the complete and detailed disclosure of the elements of the apparatus in the latter application, it is considered superfluous to duplicate herein details of construction which are not essential to an understanding of the present invention. Reference may be had to such latter application for structural details of the reader, typewriter, and control circuits and devices with which we are not directly concerned herein.

As shown in Fig. 1, the tape 10 bearing a desired coded message is wound on a supply spool 14 supported by the reader 12. The tape is fed in steps, by means not shown, past a sensing or reading station 15. A storage spool 16 is provided for receiving the tape after it is read, the latter being rotated by any suitable mechanism (not shown) through a friction drive belt 17.

The elements of the reader 12 which function to sense successively the code designations in the tape are indicated diagrammatically in Fig. 5. These elements include six sensing pins of the group S1 to S6, inclusive, which correspond, respectively, to the previously mentioned six code positions 1 to 6 inclusive in each recording field of the tape 10. The sensing pins are arranged in the same order as the code positions in Fig. 2 and in a single vertical plane extending at right angles to the direction of tape movement. The pins are located beneath the tape 10 at the sensing station 15 of Fig. 1, and the tape is fed in steps, by means not shown, past the upper ends of the pins. The arrangement is such that at the beginning of each reading operation a record field in the tape is positioned at the sensing station with the upper ends of the pins aligned with their corresponding code positions in such record field. The pins are suitably guided for vertical movement, by means not shown, and the lower ends of the pins engage, respectively, the lower spring blades 20 of pairs of sensing code contacts of the group C1 to C6 inclusive and which

also correspond, respectively, to the six code positions 1 to 6 inclusive.

The spring blades 20 are normally biased to move their related sensing pins upward and to close their related code contacts. Between sensing operations, the sensing pins S1 to S6 are held down below the tape 10, and their related contacts C1 to C6 inclusive thus held open, by a vane 21. The vane 21 is formed with an edge 22 fitting within aligned notches 23 formed in the pins S1 to S6 inclusive, and the vane is rotatably supported intermediate its ends by a fulcrum shaft 24 suitably mounted in frame elements (not shown) of the reader. A follower

15 arm 25 depends from the vane 21 and is provided at its lower end with a roller 26 engaging a cam 27 fixed to the reader shaft 28. The roller 26 is held in engagement with the cam 27 by a suitable tension spring 29 attached to the vane 21.

20 In Fig. 5, the reader elements are shown in the positions which they occupy at the beginning of a reading operation. The reader shaft is constantly rotated in a clockwise direction, as indicated by the arrow, by a reader motor which

25 is not shown structural in Fig. 5 but is indicated diagrammatically therein by the character RM. When the cam 27 moves clockwise from the position shown, the high point of such cam will move out of engagement with the roller

30 26. Because the spring 29 maintains the roller in contact with the cam, the vane 21 will then move clockwise and permit the lower spring blades 20 to move their related pins S1 to S6 inclusive upward. In those code positions of the tape

35 where code holes have been punched, the related sensing pins will pass through such holes and thereby permit sufficient vertical movement of such pins to provide for the closing of their related code contacts of the group C1 to C6 inclusive. Where there is no code hole in a code position of the record field at the sensing station, the tape stops the upward movement of the related code pin and thereby prevents the

40 clockwise movement of the cam 27 will cause the roller 26 to be engaged again by the high point of the cam which will result in the vane 21 being moved counterclockwise and thereby moving all of the sensing pins back to the position

45 shown and in thereby opening all of the code contacts. The high point of the cam 27 is of substantial length, as shown, so as to provide for spacing the tape by means not shown herein, to bring the next recording field to the sensing station 15 while the sensing pins are held out of the way and the code contacts held open.

50 As shown in Fig. 5, the pairs of code contacts C1 to C6 inclusive control, respectively, the energizing of translator relay magnets M1 to M6 inclusive. One contact point of each of the pairs of contacts C1 to C6 inclusive is connected by a separate conductor 32 to a positive supply wire 33 and the other contact point of each of said pairs of code contacts is connected by a separate conductor 34 to the supply side of its related translator relay magnet. The return sides of the translator relay magnets are all connected by a conductor 35 to a negative supply wire 36. As will be readily appreciated, the supply wires 33 and 36 are connected, respectively, to the positive and negative sides of any suitable source (not shown) of direct current supply. Thus, the closing of each of the code contacts, by the passing of its related sensing pin through a code hole in

55 the tape at the reading station, results in the

energizing of its related translator relay magnet. The relay magnets M1 to M8 inclusive are elements of a relay translator of conventional form indicated in its entirety in Fig. 5 by the numeral 40. As shown, each relay magnet controls the transfer of one or more related relay transfer contacts. The transfer contacts are each shown in their normal or upper position where the upper contact points are closed. As will be readily understood, when each of the relay magnets is energized it transfers its related contacts from such upper position to their lower or transferred position where their lower contact points are closed. Consequently, the sensing of the code designations in the tape in the manner explained above, results in selectively closing the related code contacts singly or in combination and thereby energizing their related translator relay magnets and in shifting the transfer contacts of the relays energized from their upper positions shown to their lower positions. As shown in Fig. 5, the relay transfer contacts are connected by suitable conductors in a conventional pyramid or cascade arrangement, and so that the sensing of each code designation provides for the selective adjustment of the transfer contacts to condition one circuit path through the elements of the relay translator which circuit path corresponds to the particular code designation sensed. As disclosed fully in my said copending application Serial No. 492,896, each conditioned circuit path includes a solenoid operatively connected to that key lever of the typewriter which controls the printing of the character, or the effecting of the functional operation, corresponding to the code designation which was sensed and which provided for the selective energization of the relay magnets to condition such circuit path.

As the present invention is concerned primarily with the means for controlling and effecting case shifting operations, only those solenoids which provide for the latter operations are shown. The reference numeral 41 indicates a shift solenoid and the numeral 42 a shift-release solenoid. The manner in which these solenoids provide for the case shifting operations of the typewriter will presently appear. The solenoids which operate the key levers for effecting the other functional operations of the typewriter and the solenoids which operate the character key levers of the typewriter have been omitted from the drawings as they are considered unnecessary to an understanding of the present invention. The circuit wires at the outlet side of the translator which are to be connected, respectively, to these omitted typewriter solenoids are shown in Fig. 5 as broken off and they are indicated by the reference numeral 43.

After a code designation is sensed and the corresponding circuit path through the translator conditioned in the manner above explained, such circuit path is closed by the closing of contacts 44 by a cam 45 on the reader shaft 28. The contacts 44 connect the positive supply wire 33 to the input of the translator by means of conductors 46 and 47. The output circuit wires of the translator are connected through their related typewriter key operating solenoids with the negative wire 36. At this point it is noted that for the purposes of simplicity the wiring diagram in Fig. 5 is not the same as that disclosed in my copending application Serial No. 492,896. Certain control circuits and control devices which have no particular bearing on the present invention have been omitted. Also, in the interest of

simplicity all circuits are shown as being supplied with direct current.

Referring again to Fig. 1, it is noted that the typewriter 13 is a power operated typewriter of well known commercial form and comprises the usual carriage 50 supporting a platen 51 for holding the copy sheet 52; a keyboard 53 including the usual character and functional keys; and a plurality of type bars 55 (only one type bar being shown) supported within a type basket indicated at 56 and carrying both upper and lower case type 57 and 58, respectively. The shift key is indicated at 59, the shift-lock key at 60, the shift release key at 61 and the remaining character and functional keys by the reference numeral 62.

In Fig. 3 a portion 63 of the frame part of the type basket 56 which supports the type bars, is shown. The type basket is movably mounted in the frame of the machine for case shifting movement in a well known way and the basket normally occupies an elevated position which is shown. When in such elevated position lower case characters may be typed. The shift mechanism for drawing the type basket downward to permit the typing of upper case characters is described in U. S. Patent No. 1,945,097 granted January 30, 1934, and is partly shown in Fig. 3.

Secured, respectively, to the back of the type basket frame 63 and on opposite sides thereof, are two brackets 64 (only one being shown in Fig. 3). Each bracket 64 is connected by a link 65 to the outer end of a lever arm 66. The lever arms 66 are fixed respectively, on the ends of a transverse shaft 67 journaled in the side framework (not shown) of the machine. Pivoted on a stud 68 at one side of the machine is a lever 69 having two pins 70 and 71, engageable by the short arms of a T-shaped lever 72, the later being pivotally mounted at 73 on one arm 74 of a three-armed lever 75. The lever 69 is connected by a link 76 to the outer portions of one of the lever arms 66 and at points spaced from the connection of such arm and its link 65. The T-lever 72 has a stud 77 projecting into a slot formed in an arm 78 comprising an extension of a shift key lever 79. The shift lever 79 is pivotally supported by a rod 80 carried by a stationary frame part 81, and a spring 82 connecting said lever 79 and frame part 81 biases said lever 79 to stay in its normal lower case position shown in Fig. 3. One arm 83 of lever 75 is connected by a link 84 to a cam unit 85 the operation of which is controlled by movement of the shift key lever 79.

As explained fully in the aforementioned Patent No. 1,945,097, the cam unit 85 comprises a bell crank 87 rotatably mounted on a rod 88 which is suitably supported from the frame of the typewriter by means not shown. The link 84 is connected to one end of one arm 89 of the bell crank 87 and a cam 90 is rotatably mounted on a pin 91 carried by the lower end of the other arm 92 of the bell crank 87. The cam 90 is arranged adjacent a power roller 93 which is suitably mounted in the end frame members of the typewriter by means not shown and is continually rotated by the typewriter motor TM indicated diagrammatically in Fig. 5. The cam 90 has a pair of lugs 94 and 95 projecting laterally therefrom on opposite sides of its rotary support pin 91, one or the other of such lugs being engageable by a spring-pressed arm 96 pivoted at 97 on the arm 92 of the bell crank and which tends to turn the cam 90 clockwise into engagement with the power roller. The cam also has a pair of laterally projecting stops 98 and 99 arranged on opposite

sides of and at different distances from the rotary support pin 91 and adapted to coast with a stop 100 provided on the lower end of a lever 101 also pivoted at 97 on the arm 92. The upper end of the lever 101 is provided with a laterally projecting stud 102 which is engaged within a slot 103 in the lower end of an arm 104 depending from shift key lever 79.

The type basket 56 is shifted downward to upper case position when the shift key lever 79 is depressed. The shift lever 79 may be depressed either manually by key 59 or 60 or automatically in response to a signal impulse from the translator, as will be explained more fully hereinafter. The type basket 56 is returned to its lower case position when the key lever 79 is released so that the latter may move upward under the force of its spring 82. It is therefore customary to hold the key lever 79 depressed while writing upper case characters.

In the illustrated embodiment, when the key lever 79 is depressed, the arm 104, through its slot 103, and the stud 102, rocks the lower end of the lever 101 forward or to the right as viewed in Fig. 3, and thereby moves the stop or lug 100 from engagement with stop 99 and into the path of the stop 98. This permits the cam 90 to be moved into engagement with the power roller 93 by the arm 96. Because of the engagement of arm 78 of lever 79 with the T-lever 12, when the key lever 79 is depressed the rear end of the lever 12 is elevated by the arm 78 to bring one of the short arms of the T-lever to a position at the left of pin 70. With the shift key lever being depressed, the cam 90 engages the power roller 93 and is turned thereby through one-half a revolution where its stop 98 engages the stop 100 on the arm 101. During this movement of the cam, the bell crank 87 rocks counterclockwise and then clockwise and through the link 84 and arm 83 swings the arm 74 of lever 75 forward or to the right. This action moves the T-lever 12 forward and the latter due to the position it now occupies engages the pin 70 and swings the lever 69 clockwise about its pivot pin 68. The lever 69 through the link 76 moves the lever arm 66 counterclockwise and through the link 65 pulls the type basket 56 downward to upper case position. The parts come to rest while the key lever 79 is held in its depressed or shifted position. When the key lever 79 is released so that it moves upward due to the force of spring 82, the arm 104 thereof rocks the lever arm 101 clockwise so that the stop 100 moves out of engagement with stop 98 and back into the path of lug 99. The spring pressed arm 96 again effects operative engagement of the cam 90 with power driven roller 93. Also, the arm 78 returns the T-lever 12 to the position shown in Fig. 3. The cam 90 makes another half revolution, during which the T-lever 12 is again moved forward and so that it engages the pin 71 on the lever 69 and swings the latter counterclockwise about pin 68. The link 76 is thus moved to the left as viewed in Fig. 3, which rocks the lever arm 66 clockwise and through the links 65 shifts the type basket 56 upward to its normal or lower case position.

In order to hold the key lever 79 down in its shifted position a shift-lock key lever 110 is provided. As shown in Fig. 3, the shift-lock key lever 110 is pivotally connected by a pin 111 to the shift lever 79. The shift-lock key 60 is mounted on the lever 110. The lever 110 includes a downwardly extending arm 112 terminating in a locking hook 113, and the lever is urged toward its

normal or unlocked position shown by a tension spring 114 connecting the arm 112 and the shift lever 79. An inturned flange 115 on the lever 110 engages the underside of the shift lever 79 when the shift-lock lever 110 is in its normal position and thereby serves as a stop to determine such normal position. A detent or latch plate 116 is suitably attached by a screw to a stationary part 117 of the typewriter frame and coacts with the hook 113 to hold or lock, through the lever 110, the shift lever 79 down in its shifted position.

When the shift lever 79 is moved downward to and slightly beyond a point where the cam 90 is operated to effect a case shifting operation in the manner previously explained, the shift-lock lever may be moved clockwise about its pivot pin 111 to engage the hook 113 with the latch plate 116. With the hook in this position and when the downward pressure on the shift lever is relieved, the spring 82 acting through the levers 79 and 110 will hold the hook in locking engagement with the latch plate 116. The locked position of arm 112 is indicated in dotted lines in Fig. 3. As is well known, the just described locking operation is usually manually effected by the typist first pressing downward with a finger on the shift-lock key 60 until the shift lever 79 is slightly beyond the point where case shifting is effected and then moving the shift lock key about its pin 111 to its locking position, and then relieving the pressure so that the spring 82 will hold the hook in locking engagement with the plate.

When it is desired to effect manually the return of the shift lever from the just described locked position to its normal lower case position, the shift key 59 may be depressed and thereby moved further downward a slight distance so that the hook 113 is separated from the latch plate 116. The spring 114 will then return the shift-lock lever to its normal or unlocked position. The manual pressure on the shift key 59 can then be released and the spring 82 will return the shift lever and type basket to normal lower case position.

As shown in Figs. 1 and 4 the shift lever 79 with the shift-lock lever pivoted thereto is arranged at the left-hand side of the machine. A shift-release lever 120 with the shift-release key 61 mounted thereon is arranged at the right-hand side of the machine. The shift key lever 79 may also be returned from its locked position by manually depressing the shift-release key 61. To this end, a bail lever 122 is provided which comprises a pair of end plates 123 and 124 connected by a bail rod 125 (see Figs. 3, 4, and 4a). The bail lever 122 is mounted for pivotal movement by studs 126 and 127 extending outwardly from the plates 123 and 124, and journaled, respectively, within opposite sides of the typewriter frame. A stud 128 extends inwardly from the end plate 123 and within a notch 129 formed in a downwardly extending projection 130 of shift key lever 79. A second stud 131 extends inwardly from the end plate 124 and within a notch 132 formed in a depending extension 133 of shift-release lever 120 (see Fig. 4a).

When the shift-release lever 120 is moved down either manually by depressing key 61 or automatically in response to sensing a shift-release code designation as will appear hereinafter, the extension 133 and stud 131 rock the bail lever 122 clockwise, as viewed in Figs. 3 and 4a, about its pivotal support and thereby move the stud 128 clockwise, which results in moving the shift

lever 79 downward a short distance beyond its locked position and thereby freeing the hook 113 from plate 116. The spring 114 will then return the lever 110 to its unlocked position and, when the downward acting force on the shift release lever 120 is released, the spring 82 will return the shift lever 79 and type basket 56 to normal lower case condition.

As shown in Fig. 3, the shift solenoid 41 is fixed to a stationary support plate 140 and includes a vertically movable armature 141 connected by a coil spring 142 with the outer end of the shift lever 79. The shift-release solenoid 42 (see Figs. 4 and 4a) is supported in the same manner and its armature 143 is connected by a similar coil spring 144 with the shift release lever 120. When the solenoid 41 is energized it moves the shift lever 79 downward to a position where shifting of the type basket to upper case position is effected in the manner previously described. Actually, the solenoid 41 moves the shift lever a short distance beyond the point where the cam unit 87 is tripped to effect case shifting, and thereby provides for the locking of the shift lever as will presently appear. When the shift-release solenoid 42 is energized it moves the shift-release lever 120 downward and, through the stud 131, plate 124, bail 125, plate 123, and stud 128, moves the shift lever 79 downward beyond the position occupied when held locked by the hook 113 and plate 116, so as to effect the releasing of hook 113 from the latch plate 116, in the manner previously described.

A shift-lock solenoid 150 is supported by the plate 140 directly beneath the shift-lock key lever 110. The armature 151 of the solenoid 150 is vertically movable and is connected by a pivot pin 152 to the lower end of a link 153 the upper end of the latter being in turn pivotally connected by a pin 154 to the lower end of the shift-lock arm 112. As will be seen from an examination of Fig. 3, when the shift-lock lever 110 is in its normal unlocked position, the pivot pin 154 connecting the arm 112 and link 153, is disposed to the right of an imaginary line connecting the pivot support pin 111 of the shift-lock lever and the connecting pin 152 between the lower end of the link 153 and armature 151. Thus, the arm 112 and link 153 are in effect the two links of a toggle which is broken when the shift-lock lever occupies the unlocked position shown in Fig. 3.

When the solenoid 41 is energized and thereby moves the shift lever 79 downward to and beyond its shifted position as explained above, then the energizing of the shift-lock solenoid 150 and the resulting downward vertical movement of the armature 151, will tend to straighten the above mentioned toggle connection and will thereby move the pin 154 toward the left as viewed in Fig. 3. This will result in the hook member 113 being moved into locking position beneath the catch plate 116. When the shift-lock solenoid 150 is deenergized and with the shift lever moved downward beyond the locking point, the spring 114 will move the arm 112 and link 153 back to the position shown in full lines in Fig. 3.

In accordance with the present invention, means is provided for differentially energizing the solenoids 41 and 150 in response to the sensing of a "shift" code designation in the tape 10, and in such a manner that the shift lever 79 is first moved downward to and beyond a point where case shifting is effected and, while in this

position, the shift-lock lever 112 is moved from the position shown in full lines in Fig. 3 to a locking position where the hook 113 is beneath the catch plate 116.

From an examination of Fig. 2, it will be noted that the "shift" code designation comprises code holes in code positions 1, 2, 4, and 5. Referring to Fig. 5, it will be apparent that the sensing of code positions 1, 2, 4, and 5 energizes translator magnets M1, M2, M4, and M5 which shift their respective relay transfer contacts to their lower or shifted position and thereby condition a circuit path which is traced as follows: from the positive supply wire 33; through the conductor 46; cam contacts 44; conductor 47; transfer contacts M1—1 and M2—2, in shifted position; transfer contacts M3—4, in the position shown; transfer contacts M4—7 and M5—14, in shifted position; transfer contacts M6—28, in the position shown; wire 160; and through the shift solenoid 41 and the coil of a relay 161, connected in parallel, to the negative supply wire 36. Thus, upon the subsequent closing of a cam contacts 44 the just traced circuit is closed thereby and the shift solenoid 41 and coil of relay 161 are energized simultaneously. As explained above, the energizing of the shift solenoid will result in the shift lever 79 being drawn down to and beyond the point where case shifting is effected.

The relay 161, when energized, closes its contacts 162 and thereby connects the shift-lock solenoid 150 across the power source by a circuit traced as follows: from the supply wire 33, through a conductor 164, contacts 162 now closed, solenoid 150, to the negative supply wire 36. It is noted that the solenoid 41 and relay 161 are energized simultaneously by the signal impulse and that solenoid 150 is energized one step afterwards upon the closing of relay contacts 162. The energized shift-lock solenoid 150 moves the shift-lock lever 110 to its previously described locking position where the hook member 113 is beneath the latch plate 116.

When the contacts 44 are opened by the cam 45 the signal impulse, transmitted through the translator to the shift solenoid 41 and relay 161, terminates, thereby simultaneously deenergizing the shift solenoid 41 and the relay 161. The relay 161 when deenergized opens its contacts 162 and the circuit through the solenoid 150. Thus, the solenoid 150 is deenergized one step after the solenoid 41. It is also noted that the relay 161 is a slow acting relay so that its contacts 162 open a substantial time interval after the solenoid 41 has become deenergized sufficiently to release its armature 141. As the shift-lock solenoid is held energized this short time interval after the deenergizing of the shift solenoid, the hook member 113 will be held thereby in its locking position beneath the plate 116. Consequently, as the solenoid 150 becomes deenergized, the spring 82 will move the shift lever 79 and shift-lock lever 110 upward and thereby effect the previously described locking engagement of the hook 113 and the latch plate 116.

The just described differential energizing and differential deenergizing of the shift and shift-lock solenoids in response to a "shift" signal impulse, provides an effective and dependable means for automatically effecting case shifting. As the shift lever is pulled downward to and beyond its shifted position before the shift-lock lever is moved into locking engagement, there is no possibility of the hook striking the upper surface of the plate 116 in such a manner as would pre-

vent the effective locking of the shift lever in its shifted position.

Referring again to Fig. 5, it will be apparent that upon the sensing of a "release" code designation, which as is shown in Fig. 2, is a code hole in each of code positions 1, 2, 3, 4, and 5, a circuit path through the translator is conditioned, which circuit path also includes the shift-release solenoid 42. The conditioned circuit path is traced as follows: from positive wire 33; conductor 46; cam contacts 44; conductor 47; relay transfer contacts M1—1, M2—2, M3—4, M4—8, and M5—16 in their shifted positions; transfer contacts M6—32, as shown; wire 170; and shift-release solenoid 42 to the negative wire 36. As before, when the cam contacts 44 close the just traced conditioned circuit path is established and shift-release solenoid 42 is energized thereby pulling the shift-release lever 120 downward. The lever 120, through the stud 131, plate 124, bail 125, plate 123, and stud 128 pulls the shift lever 79 downward and beyond its locked position in the manner previously described. This will result in releasing the hook 113 from the plate 116 and in the spring 114 moving the shift-lock lever 110 about its pivot pin 111 to its unlocked position; and, when the "release" signal impulse terminates with the opening of the cam contacts 44, the shift-release solenoid 42 becomes deenergized and the spring 82 will return the shift lever 79 to its normal or lower case position which will result in the shifting of the type basket to normal lower case position, as was described in detail hereinabove.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In signal controlled printing apparatus of the type wherein case shifting is effected by the movement of a shift lever against the force of a spring from a normal position to a second position and wherein said shift lever is held locked in said second position by a hook pivoted to said shift lever and engageable with a stationary latch member, the combination with said lever, hook, and latch member, of a first magnet operable when energized to move said shift lever to said second position; a second magnet operable when energized to move said hook from an unlocked position to a locking position where it operatively engages said latch member when said first magnet is deenergized; means providing a signal impulse; and electrical circuit means including said magnets and responsive to said signal impulse means for energizing said first magnet first and then energizing said second magnet and for de-energizing said first magnet first and then deenergizing said second magnet.

2. In signal controlled printing apparatus of the type wherein case shifting is effected by the movement of a shift lever against the force of a spring from a normal position to a second position and wherein said shift lever is held locked in said second position by a hook pivoted to said shift lever and engageable with a stationary latch member, the combination with said lever, hook,

and latch member, of a first magnet operable when energized to move said shift lever to said second position; a second magnet operable when energized to move said hook from an unlocked position to a locking position where it operatively engages said latch member when said first magnet is deenergized; means providing a signal impulse; and electrical circuit means comprising a first circuit for transmitting said signal impulse and including said first magnet and a relay having normally open contacts, and a second circuit connected across a power source and including said second magnet and said normally open relay contacts.

3. Signal controlled printing apparatus comprising a case shift lever movable from a normal case position to and beyond a shifted case position; a first spring urging said shift lever back to normal case position; a stationary latch member; a shift-lock arm pivoted to said shift lever and including a hook; a second spring urging said arm toward an unlocked position; the construction and arrangement of said shift lever, arm and latch member being such that with said lever beyond its said shifted position, said arm may be rocked to a locking position where, when said shift lever is then returned toward normal position, said hook engages said latch member and is held latched with respect thereto by said first spring; a first magnet connected to said shift lever and operable when energized to move the latter to and beyond its said shifted position; a second magnet connected to said arm and operable when energized to move the latter to its said locking position; means providing for a signal impulse; and electrical circuit means including said first and second magnets and responsive to said signal impulse means for differentially energizing and then differentially deenergizing said first and second magnets so that said first magnet is energized before said second magnet is energized and is deenergized before said second magnet is deenergized.

4. Signal controlled printing apparatus comprising a case shift lever movable from a normal case position to and beyond a shifted case position; a first spring urging said shift lever back to normal case position; a stationary latch member; a shift-lock arm pivoted to said shift lever and including a hook; a second spring urging said arm toward an unlocked position; the construction and arrangement of said lever, arm and latch member being such that with said lever beyond its shifted position, said arm may be rocked to a locking position where, when said shift lever is then returned toward normal position, said hook engages said latch member and is held latched with respect thereto by said first spring; a first magnet connected to said shift lever and operable when energized to move the latter to and beyond said shifted position; a second magnet connected to said arm and operable when energized to move the latter to its said locking position; means providing for a signal impulse; and electrical circuit means including said first and second magnets and operable upon the transmission of a signal impulse, to energize said first magnet and then to energize said second magnet after a relatively short time delay, and operable upon the termination of the transmission of said impulse, to deenergize the first magnet, and then to deenergize said second magnet after a relatively short time delay.

5. Signal controlled printing apparatus comprising a case shift lever movable from a normal

case position to and beyond a shifted case position; a first spring urging said shift lever back to normal case position; a stationary latch member; a shift-lock arm pivoted to said shift lever and including a hook; a second spring urging said arm toward an unlocked position; the construction and arrangement of said lever, arm and latch member being such that with said lever beyond its shifted position, said arm may be rocked to a locking position where, when said shift lever is then returned toward normal position, said hook engages said latch member and is held latched with respect thereto by said first spring; a first magnet connected to said shift lever and operable when energized to move the latter to and beyond its said shifted position; a second magnet connected to said arm and operable when energized to move the latter to its said locking position; means providing for a signal impulse; and electrical circuit means comprising a first circuit for transmitting said signal impulse and including said first magnet and a relay having normally open contacts, and a second circuit connected across a power source and including said second magnet and said normally open relay contacts.

6. Signal controlled printing apparatus comprising a case shift lever movable from a normal case position to and beyond a shifted case position; a first spring urging said shift lever back to normal case position; a stationary latch member; a shift-lock arm pivoted to said shift lever and including a hook; a second spring urging said arm toward an unlocked position; the construction and arrangement of said lever, arm and latch member being such that with said lever beyond its shifted position, said arm may be rocked to a locking position where, when said shift lever is then returned toward normal position, said hook engages said latch member and is held latched with respect thereto by said first spring; a shift-release lever movable from a normal to a release position; means operatively connecting said shift-release lever and said shift lever so that movement of said shift-release lever to said release position moves said shift lever beyond its said shifted position; a first magnet connected to said shift lever and operable when energized to move the latter to and beyond its said second position; a second magnet connected to said arm and operable when energized to move the latter to its said locking position; a third magnet connected to said shift-release lever and operable when energized to move said shift-release lever to its said release position; impulse

means selectively providing for a shift signal impulse and for a shift-release signal impulse; electrical circuit means including said first and second magnets and responsive to said impulse means providing a shift signal impulse, for differentially energizing and deenergizing said first and second magnets so that said first magnet is energized before said second magnet is energized and is deenergized before said second magnet is deenergized; and a second electrical circuit means including said third magnet and responsive to said impulse means providing a shift-release signal impulse, for energizing said third magnet.

7. In signal controlled printing apparatus, a case shift lever movable downward from a normal case position to and beyond a predetermined shifted case position; a first spring urging said shift lever to return to said normal case position; a stationary catch plate below said shift lever; a shift-lock arm pivoted to said shift lever and extending downwardly therefrom and including a hook so formed that when said shift lever is beyond said adjusted position said arm may be rocked from an unlocked position to a locked position where said hook will engage beneath said plate when said shift lever returns toward normal case position; a second spring urging said arm to said unlocked position; a first magnet connected to said shift lever and operable when energized to move the latter downward and beyond said shifted position; a second magnet beneath said arm and including an armature movable downward when attracted; a link pivoted at one end to the upper end of said armature and extending upwardly therefrom and pivoted at its upper end to the lower end of said arm; said arm, link, and armature being so arranged that with said arm in unlocked position the pivot between said arm and link is at the side of a straight line joining the pivot between said arm and shift lever and the pivot between said link and armature, which is away from said catch plate, whereby when said second magnet is energized and its armature moves downward said hook is rocked toward said catch plate and into said locked position; means providing for a signal impulse; and electrical circuit means including said first and second magnets and responsive to said signal impulse means for differentially energizing and deenergizing said first and second magnets so that said first magnet is energized before said second magnet is energized and is deenergized before said second magnet is deenergized.

HENRY L. THOLSTRUP.
